Charles R. Searle
ATTORNEY

UNITED STATES PATENT OFFICE.

TIMOTHY J. FOLEY, OF NEW YORK, N. Y.

FASTENING FOR TOOL HANDLES.

1,412,610.

Specification of Letters Patent.

Patented Apr. 11, 1922.

Application filed February 15, 1921. Serial No. 445,084.

To all whom it may concern:

Be it known that I, TIMOTHY J. FOLEY, a citizen of the United States, residing in the city of New York, borough of Bronx, in the 5 county of Bronx and State of New York, have invented a certain new and useful Improvement in Fastenings for Tool Handles, of which the following is a specification.

The invention relates to means for fastening handles to tools, and the object of the invention is to provide a fastening means which shall hold reliably and insure against accidental release of the tool, avoid danger of splitting or otherwise damaging the 15 handle, and permit the latter to be removed for the substitution of a new handle when required.

The invention consists in certain details of construction by which the above objects 20 are attained, to be hereinafter described and claimed.

The accompanying drawings form a part of this specification and show approved forms of the invention.

25 Figure 1 is a side view of a hammer head and portion of its handle, joined by my improved fastening means.

Figure 2 is a corresponding section taken on the line 2—2 in Figure 1.

30 Figure 3 is a section taken longitudinally of a tool and handle, of the chisel type.

Similar letters of reference indicate like parts in all the figures.

Referring to Figures 1 and 2, A is the 35 head of a hammer having a socket B and handle C extending through the socket and head.

In the opposite faces of the socket, at any 40 convenient point, holes b are drilled and tapped, and the handle C is bored to receive an interiorly threaded bushing D located to register with the holes b when the handle is fully home in the head. A screw F matching the threads in the holes b and bushing 45 D is driven through the socket and handle and its protruding end upset or riveted, as at F¹.

Thus joined the head is securely fastened to the handle and accidents due to the "flying off" of the head are avoided.

The bushing D serves to protect the wood from distortion or splitting under the various strains to which the tool is subjected in service. The usual wedges driven from 55 the top of the head to spread the handle and fill the eye, may be omitted and the

damage by splitting the handle due to such wedges may be avoided.

To insure against oscillatory movements of the handle and head relatively to each other, two of such fastening means located at separated points may be employed, as shown in Figure 1.

In the event of the handle being broken, it may be removed by filing off the riveted 65 end of the screw and the latter turned in the direction to withdraw it. The handle may then be driven from the socket and a new handle similarly equipped inserted and fastened by a similar screw.

Although Figures 1 and 2 show the tool as a hammer it will be understood that the same means of fastening may be applied to hatchets, axes, adzes and all tools of that or other type having an eye or a socket receiving a handle.

Figure 3 shows a tool of the chisel type having a tang E received in a handle G. The tang and handle are both bored to receive a bushing D¹ extending through both 80 with its ends flush with the outer faces of the handle and inclosed in a ferrule H which is bored to receive a rivet J extending through the ferrule and bushing and headed to prevent its withdrawal.

This form of the invention is especially applicable to all tools of the chisel or screw-driver type and to hoes, rakes and the like having a tang thrust into a handle.

The improved fastening means adds but 90 little to the cost of manufacture and the security attained through the use of the invention renders the cost negligible.

I claim:—

1. A tool having a socket, the latter having oppositely located screwthreaded holes, a handle received in said socket, a tubular bushing extending transversely of said handle, and a screw received in said holes and extending through said socket and bushing and closely fitting the same.

2. A tool having a socket, the latter having oppositely located screwthreaded holes, a handle received in said socket, an interiorly screwthreaded tubular bushing extending 105 transversely of said handle, and a screw matching the threads in said holes and bushing and closely fitting the bushing and extending through said socket and handle.

In testimony that I claim the invention 110 above set forth I affix my signature.

TIMOTHY J. FOLEY.
